his ATTORNEY.

UNITED STATES PATENT OFFICE.

AMLETO SELVATICO, OF MILAN, ITALY.

ELECTRIC STOVE.

Application filed August 13, 1921. Serial No. 492,072.

To all whom it may concern:

Be it known that I, AMLETO SELVATICO, subject of the King of Italy, and resident of Milan, Italy, have invented certain new and useful Improvements in Electric Stoves (for which I filed an application in Italy, July 20, 1920), of which the following is a specification.

The present invention relates to an electric stove, wherein a current of air is caused to circulate internally and around the heating element, said current being conducted by means both of a central column and of reflection against either the grate or the upper oven plate designed to support the object to be heated, so as to obtain a maximum utilization of the generated heat.

A form of the invention is illustrated in the accompanying drawing, in which:

Fig. 1 is a vertical section of the stove, and

Fig. 2 is a plan view, partially in section, of the same.

Referring to the drawing, 1 is the base of the stove support, from which the uprights 2 extend, said base being provided with the rods 3 and 4, upon which, by means of plates 3' and 4', a hollow cylinder 6 either of porcelain or of any other suitable material is mounted, which cylinder is provided with the washer 6' and covered with a winding of wire 5, said wire being connected to terminals 7 and 8 by means of said metallic rods 3 and 4 and of the conductors 7' and 8'.

The uprights 2 are adapted to support a substantially bowl shaped reflector 10 having an open bottom 12 designed to rest on the washer 6', and an open top stepped as indicated at 11 and 13. The upper step or shoulder 13 serves to support a plurality of concentric rings 14, or their equivalent,

upon which the article to be heated may be placed. The rings are preferably provided with openings 15 for the passage of air, and with ribs 16 to facilitate circulation of air under the receptacle or other article resting on the rings 14.

In operation, cold air enters the cylinder 6 through its lower open end, is heated in the cylinder and then flows through the top of the cylinder into the reflector 10 wherein it is further heated, and finally flows upwardly against the rings 14 and around the receptacle resting thereon, effectively heating such receptacle and its contents if there be any.

Having now particularly described and ascertained the nature of my invention and in what manner the same is to be performed, what I claim is:

1. In a device of the character described, the combination with a supporting structure including a supporting member, of a reflector having an open upper end and an open lower end resting on said supporting member, an air conduit carried by said supporting member and projecting into said reflector, and means for heating said air conduit.

2. In a device of the character described, the combination with a supporting structure including a supporting member, of a cylinder of heat resistant material carried by said supporting member, a reflector completely enclosing said cylinder and having an open lower end resting on said supporting member, a resistance coil about said cylinder, and means for conducting electric current to said coil.

Signed at Milan, Italy, this 21st day of VII A. D. 1921.

AMLETO SELVATICO.
